INVENTOR:

Albert Wahl.

UNITED STATES PATENT OFFICE.

ALBERT WAHL, OF MILWAUKEE, WISCONSIN.

IMPROVEMENT IN EXERCISING APPARATUS.

Specification forming part of Letters Patent No. 175,581, dated April 4, 1876; application filed November 5, 1875.

To all whom it may concern:

Be it known that I, ALBERT WAHL, of Milwaukee, in the county of Milwaukee, in the State of Wisconsin, have invented certain Improvements in Gymnastic Exercisers, of which the following is a specification:

The object of my invention is to straighten the backs of the crooked, and for gymnastic exercises generally. It is a machine with a roller for the back to rest on and a bar for the hands to take hold of, and draw the back across the roller.

Figure 1 is a perspective view of my invention.

A is the platform, on which the apparatus stands; B B, the standard which supports a roller; C, a cross-bar between the standard, through which a brace passes; D, a roller across the top of standard B; E, a brace which holds standard F in place; G, a pin which holds brace E into standard F; H, a pin which holds brace E into cross-bar C; I, handle on the top of standard F.

This machine may be made with one standard instead of two and the brace C passing

through it, and a frame on top in which roller D runs.

K, pin which passes through ears L and the foot of F, and may be shifted into the hole back of the one in which it now is to adjust standard F to the work it has to do. The brace E may be lengthened out or shortened up, as may be necessary, and the pin H adjusted so as to make it right.

Operation: Lean over the roller D and reach over and with the hands take hold of the handles I and draw the back back and forth over the roller, and the back will be straightened and the exercise will be good.

I claim as my invention—

1. In an exercising-machine, the brace E, standard B, and roller D, in combination with standard F, substantially as set forth.

2. The standard B, roller D, cross-bar C, and adjustable brace E, in combination with standard F, substantially as described.

ALBERT WAHL.
